ABSTRACT OF THE DISCLOSURE

A hermetically sealed hull for undersea exploration assembled from predetermined elements of arcuate tank ends by welding.

This invention relates in general to the construction of submersible crafts or hulls adapted for oceanography observation and other marine functions and more particularly to an economical construction for a symmetrical hull adapted to withstand high static hydraulic pressures.

Prior construction for hulls of this general character required elaborate expensive forming dies for producing three dimensional elements made from heavy sheet material by means of progressive die operation in high impact presses. Thus, the construction of a relatively low production of enclosed hulls by usual well known procedures is exceedingly expensive.

The present method involves a new form of construction adapted to the use of well known existent formed sheet metal parts including the use of a cutting and assembly process, to be hereinafter described, which construction results in a symmetrical submersible hull having great resistance to high static pressure, which construction is accomplished at relatively low cost.

A further object of the invention is the provision of a totally enclosed symmetrical submersible hull including a vertical tubular column centrally positioned in said hull between the upper and lower side to serve as a reinforcement compression member and as a ballast tank.

A further object of the invention is the provision of a symmetrical submersible hull in which a pair of generally U-shaped vertical supports are shaped to conform to the inner sides of said hull for reinforcing same and providing ballast tanks for submergence and lateral stability.

These and other objects and advantages in two embodiments of the invention are described and shown in the following specification and drawings, in which:

FIG. 1 is a perspective view of a standard circular flanged dished tank head in reduced scale.

FIG. 2 is a perspective view of two of the heads shown in FIG. 1 in spaced facing juxtaposition and having a central portion of uniform width, illustrated in dotted lines in FIG. 1, cut away and discarded.

FIG. 3 is a perspective view illustrating the edges of the sectors shown in FIG. 2 secured to each other forming a hollow hull with a portion thereof broken away.

FIG. 4 is a cross sectional view taken through section line 4—4, FIG. 3.

FIG. 5 is a cross sectional view taken through section line 5—5, FIG. 3.

FIG. 6 is a perspective view illustrating an alternative construction utilizing complete opposite halves of the element shown in FIG. 1 with a congruent arcuate element of uniform width positioned therebetween.

FIG. 7 is a perspective view of a hull formed by two sets of the three elements shown in FIG. 6 with the edges thereof secured together.

FIG. 8 is a cross sectional view taken through section line 8—8, FIG. 7.

FIG. 1 shows a typical tank head H of ellipsoidal dished form which is manufactured by quantity production by spinning and die forming methods and is one of many

2

shapes readily available for use as end members in the fabrication of large cylindrical tanks of a wide variety of sizes used in industry. In this particular embodiment, for illustration only, the head 1, shown in FIG. 1, is approximately sixteen feet in diameter and formed from steel of uniform thickness of a half inch and is cut through along dotted lines 2 and 3, which lines lie in a pair of central uniformly spaced vertical planes with respect to the principal axis of the head a—a, thus forming sectors 4 and 5 and the discard of the element 1 between the dotted lines 2 and 3.

A second like head is cut in the identical manner and forms lower sectors 6 and 7, positioned for assembly as illustrated in FIG. 2.

FIG. 3 shows the sectors 4, 5, 6, and 7 secured together preferably by a horizontal peripheral weld 8 and a circumferential weld 9 in a vertical plane, as illustrated, thus forming an elongated hollow hull which is generally streamlined for movement when submerged in water and inherently highly resistant to deformation from static pressure in all directions.

It is to be noted that the sectors may be satisfactorily joined by well known double riveted butt points instead of by welding.

Since the bottom and top areas of the hull are subject to the greatest static stress, a pair of hollow steel vertical columns 10 are centrally positioned and secured, preferably by welding, to the upper and lower inner surfaces at the junction of sectors 4, 5, 6, and 7, as shown. These columns also may be used as ballast tanks for controlling the fore and aft attitude of the hull when submerged. In order to further reinforce the upper and lower halves of the hull, a starboard and a port tank 11 and 12, respectively, are formed in generally U-shape from sheet steel and welded to the inner surfaces of each lower half at each side thereof, as shown. These compression reinforcements may also serve as ballast tanks for buoyancy control of the hull and for trimming the lateral attitude thereof. The cross sectional FIGURES 4 and 5 more clearly illustrate the longitudinal and transverse shape of the hull as well as the reinforcements therein.

It is now apparent that the length of the aforesaid hull is substantially equal to the diameter of the heads from which it is constructed. FIGURES 6, 7, and 8 illustrate an alternate hull in which the aforesaid dished heads, like that shown in FIG. 1, are bisected through a single central plane and the sectors are shown as 4a, 5a, 6a, and 7a. However, instead of joining the sectors, as previously described, a pair of like arcuate members 13 of predetermined uniform width and thickness are formed to edgewise coincide with the opposite edges of the mating sectors 4a—6a and 5a—7a, as shown in FIGS. 7 and 8. The elements described are retained by a horizontal peripheral weld 14 and a pair of like circumferential welds 15—15 in a vertical plane which will complete the enclosure of the hull. As heretofore described, columns 10a may be centrally positioned to reinforce the upper and lower sections of the hull against vertical static pressures as well as the use of tanks 11 and 12 previously described serving as additional reinforcements and ballast tanks.

It is apparent that well known hermetically sealed entry hatches, not shown, and observation windows 16—16, as illustrated in FIG. 3, may be placed in the hull in appropriate positions as required.

Having described our invention, we claim:

1. A method of constructing a totally enclosed symmetrical submersible hull consisting of a first step of cutting a pair of like standard dished circular tank heads of substantially uniform thickness along two planes parallel the principal axis thereof and at a predetermined equi-spaced distance there-

- from and discarding the center portions thereof forming two pairs of like sectors having planar cut edges, a third step of joining together the peripheral edges of each pair of said sectors together forming a hermetic junction,
 5 a third step of joining together the peripheral edges of each pair of joined sectors forming another hermetic junction and completing a hollow generally ellipsoidal hull.
2. The method of constructing a totally enclosed symmetrical submersible hull consisting of
 10 a first step of cutting a pair of like metal standard dished circular tank heads of substantially uniform thickness along two planes parallel the principal axis thereof and at a predetermined equi-spaced distance therefrom and discarding the cut off center portions thereof having a pair of planar cut edges,
 15 a second step of welding each pair of said cut edges together forming a hermetic junction,
 a third step of welding the peripheral edge of each said pair of said joined sectors forming a peripheral hermetic junction and completing a hollow generally ellipsoidal hull.
3. A method of constructing a totally enclosed symmetrical submersible hull consisting of
 20
 25

- a first step of cutting a pair of like standard dished circular tank heads of substantially uniform thickness along a plane through the principal axis thereof forming two pairs of like sectors having planar cut edges,
 a second step of preparing two like members of pre-determined width and said like thickness and shaped to conform with the cut edges of said sectors,
 a third step of hermetically joining the said cut edges of each of said sectors to each opposite edge of each of said members forming two halves of a hull with each having a like shaped peripheral edge,
 a fourth step of hermetically joining said peripheral edges of each of said halves and forming an enclosed hull of generally ellipsoidal shape.
